UNITED STATES PATENT OFFICE.

EDWARD LINCOLN PITTS, OF JEROME, ARIZONA TERRITORY, ASSIGNOR OF ONE-HALF TO WILLIAM McK. PARKS, OF JEROME, ARIZONA TERRITORY.

COLLAR OR CUFF HOLDER.

SPECIFICATION forming part of Letters Patent No. 752,587, dated February 16, 1904.

Application filed November 3, 1903. Serial No. 179,714. (No model.)

To all whom it may concern:

Be it known that I, EDWARD LINCOLN PITTS, a citizen of the United States, and a resident of Jerome, in the county of Yavapai and Territory of Arizona, have made certain new and useful Improvements in Collar or Cuff Holders, of which the following is a specification.

My invention is an improvement in devices for holding cuffs and for holding collars in place when in use; and the invention consists in certain novel constructions and combinations of parts, as will be hereinafter described and claimed.

In the drawings, Figure 1 is a front elevation of the device in use as a collar button or holder. Fig. 2 is a detail section on about line 2 2 of Fig. 1. Fig. 3 is a perspective view of the invention in connection with a cuff, the holder being open. Fig. 4 is a detail perspective view of the holder, and Fig. 5 is a detail enlarged section of a portion of the holder, taken on about the same line as Fig. 2.

The holder, as shown, comprises two sections A and B, which are hinged together at C and curved slightly toward the hinged joint C at A' and B', so the sections A and B will be spread apart when the holder is closed, as shown in Fig. 1, sufficiently to extend on opposite sides of the cuff or collar, as best shown in Fig. 2 of the drawings. These sections A and B are hinged together at one end and are provided at their outer ends with interlocking devices, and one of the sections has at its outer end the divided button D to engage in the neckband of the shirt, as shown in Fig. 2, or to engage with the wristband of the sleeve in the use of the device as a cuff-holder, as shown in Fig. 3 of the drawings.

By preference the button D, having the fixed section D' and the swinging section D'', has its shank d' secured to the section A near the outer end thereof. In inserting and removing the button the wing D'' may be turned to coincide with the wing D' and is provided at its outer edge with a projecting lug d'', which overlaps the outer edge of the wing D', as will be understood from Figs. 2 and 4 of the drawings. The lug d'', overlapping the outer

edge of the wing D', covers the joint between the wings D' and D'', when the latter are turned to register with each other and provides practically a solid point for the button D in such arrangement of the parts. At its outer end the section A is also provided with a socket E, arranged on the opposite side of the section A from the button D and open at its outer end at e to receive the spring-catch F on the section B and provided at such outer end with the lip or projection e' to engage with the shoulder f of the spring-catch F when the said catch is forced into the socketed head E, as shown in Figs. 2 and 5 of the drawings.

The catch F is composed of a strip of spring material secured at f' to the inner side of the section B of the holder, curved thence into the form of a bow f'', adapted to be forced into the socketed head E, and having its free wing f''' shouldered at f to engage the lip e'. Said free wing f''' is guided in a slot b in the outer end of the section B and is provided with a button or head F', lying outside of the section D and giving a finish to the appearance of the device as well as serving as a handle by which to release the catch F from the socket E in the use of the invention.

In use the device may be buttoned by the button D to the neckband, as shown in Fig. 2, or to the wristband, as will be understood from Fig. 3, and the socketed head E be forced through the buttonhole of the collar or cuff, as the case may be, and the section B be then adjusted over the collar or cuff and the spring-catch F be forced into the socketed head E to secure the collar or cuff, as desired.

The device is simple, can be inexpensively made or can be ornamented to any desired extent, and can be readily applied for use.

Having thus described my invention, what I claim as new, and desire to secure by Letters Patent, is—

1. A holding device for collars or cuffs substantially as herein described comprising two sections hinged together at one end and slightly curved toward their said hinged joint, a socketed head on one side of one of said sec-

tions at its outer end, a sectional button on the opposite side of such section from the socketed head, the other section being provided in its outer end with a slot, the spring-catch secured at one end to said slotted section and having a bowed portion to interlock in the socketed head and provided at its free end with a button, the free wing of the bow being arranged to operate in the slot of the section, substantially as set forth.

2. A holder for collars or cuffs composed of two sections hinged together at one end, a socketed head at the outer end of one of said sections and projecting between the two sections, a spring-catch at the outer end of the other section to interlock with said socketed head, and a button on one of the sections to connect with the garment, substantially as set forth.

3. A collar or cuff holder composed of two sections jointed together at one end, one of the sections having at its outer end a socketed head, such head being open at its end and provided with a lip or projection and the other section having a spring-catch fitted to enter the socketed head and shouldered to engage with the lip or projection thereof, the socketed head lying between the two sections and being adapted to fit in a buttonhole in a garment placed between the sections, substantially as set forth.

4. A holder comprising the two sections connected together, one of said sections being

provided in its outer end with a slot, the spring-catch secured at one end to said section, bowed between its ends and operating adjacent to its other end in the slot of the section, and the socketed head on the other section in position to receive the spring-catch, substantially as set forth.

5. The combination in a holder for collars or cuffs of the two sections hinged together, one of the sections having the slot in its outer end, the bowed spring-catch secured at one end to the slotted section and having a wing operating in the slot thereof and a shoulder to engage with a socketed head, and a socketed head on the other section in position to receive the spring-catch and having a lip or projection for engagement with the shoulder of the spring-catch, substantially as set forth.

6. A holder for collars or cuffs comprising the sections connected together at one end, the socketed head at the outer end of one of said sections, and the spring-catch at the outer end of the other section and composed of a strip of spring material secured at one end to its supporting-section and provided at its free end with a button, substantially as and for the purpose set forth.
